F. O. BALL

REATOMIZER

Filed April 2, 1921

UNITED STATES PATENT OFFICE.

FREDERICK O. BALL, OF DETROIT, MICHIGAN, ASSIGNOR TO BALL AND BALL CARBURETOR COMPANY, A PARTNERSHIP COMPOSED OF FREDERICK C. BALL AND CORNELIA M. BALL, OF DETROIT, MICHIGAN.

REATOMIZER.

Application filed April 2, 1921. Serial No. 458,136.

To all whom it may concern:

Be it known that I, FREDERICK O. BALL, a citizen of the United States, residing at Detroit, in the county of Wayne and State 5 of Michigan, have invented new and useful Improvements in Reatomizers, of which the following is a specification.

This invention is designed to atomize liquids which are deposited on the walls of intake passages leading to explosive engines. Such devices have heretofore been made but this construction increases the spraying action of the device and simplifies its construction. It also offers comparatively little resistance to the inflowing mixture.

The invention is illustrated in the accompanying drawings as follows:—

Fig. 1 shows an explosive engine in section through the intake manifold.

Fig. 2 a bottom view of the re-atomizer.

Fig. 3 a section on the line 3—3 in Fig. 1.

Fig. 4 a bottom view of an alternative construction.

Fig. 5 a section on the line 5—5 in Fig. 4.

25 1 marks the cylinders, 2 the intake manifolds having the intake passage 2^a, and 3 a carburetor controlled by the usual throttle 4. I have shown an especial type of carburetor but it will be understood that any carburetor 30 may be used with this device.

The intake passage 2^a is provided with a flange 5 and the carburetor with a flange 6 to facilitate securing them together. I insert between these flanges a fitting 7 in the 35 form of a ring and clamp it between the flanges 5 and 6 by means of screws 7^a.

The fitting 7 has an annular groove 8 in its upper face and its walls as 9 are outside of the line of the walls of the intake passage, 40 these walls tapering toward the bottom end 10 to the top of the carburetor. A re-atomizer ring 11 is inserted within the walls 9 and there is formed between the ring 11 and the wall 9 an annular chamber 12, the lower 45 end of the ring forming a lip leading from the chamber and the chamber having an annular opening to the intake passage so as to obstruct and receive ingoing liquid. The ring is provided with a flange 13 which seats 50 in the annular groove 8 and is clamped in place as the fitting is clamped in place. A nozzle in the form of a Venturi tube 14 is arranged at the center of the ring 11 and mounted on bars 15 leading to the ring, these

bars having passages 16 connecting the 55 chamber 12 with the throat of the Venturi tube.

It will readily be observed that as the liquid follows up the walls of the carburetor it is obstructed and received into the 60 chamber 12 carried by the passages 16 to the Venturi tube where it is again sprayed into the ingoing mixture. The Venturi tube creating a low point of pressure induces a 65 flow of fluid or mixture into the chamber 12 out through the passage so as to facilitate the collecting of any ingoing liquid and also to thoroughly break up this liquid and deliver it into the ingoing mixture in the form 70 of spray.

I prefer to provide the intake passage with a passage venturi 17. This is formed of spun sheet metal with a throat 18 at the elevation of the discharge of the venturi 14 so as to give a double venturi effect. The 75 Venturi tube 17 is provided with a flange 19 which is seated over the flange 13 and clamped in place with the ring as the fitting 7 is clamped in place.

The ring 11 with its parts forms a very 80 shallow construction which can be readily formed by die casting in a single operation and gives an efficient construction in that it offers very little resistance to the inflowing air and also induces a very high spraying 85 effect through the passages 16.

In the alternative construction the ring 13^a is one that may be pressed into the passage and this ring is connected by the bar 15^a with the Venturi tube 14^a operating as 90 the Venturi tube 14 in the preferred construction.

What I claim as new is:—

1. A re-atomizer comprising a ring forming a chamber; a nozzle discharging into the mixture passing through the ring; a connection between the nozzle and the chamber and a Venturi tube seated on the ring and having its throat in operative relation to the discharge of the nozzle.

2. A re-atomizer comprising a ring forming a chamber; a nozzle discharging into the mixture passing through the ring; a connection between the nozzle and the chamber and a Venturi tube seated on the ring and having its throat in operative relation to the discharge of the nozzle, said nozzle being in the form of a Venturi tube.

3. In a re-atomizer, the combination of a fitting having a seat therein and an annular groove forming one wall of a chamber; a re-atomizer ring seated in the seat in the fitting and forming with the groove a chamber receiving an ingoing liquid; a nozzle connected with the chamber and carried by the ring and discharging into the mixture passing through the ring, and a connection between the nozzle and the chamber.
4. In a re-atomizer, the combination of a fitting having a seat therein and an annular groove forming one wall of a chamber; a re-atomizer ring seated in the seat in the fitting and forming with the groove a chamber receiving an ingoing liquid; a nozzle carried by the ring and discharging into the mixture passing through the ring; a connection between the chamber and the
5. In a re-atomizer, the combination of a fitting having a seat therein and an annular groove forming one wall of a chamber; a re-atomizer ring seated in the seat in the fitting and forming with the groove a chamber receiving an ingoing liquid; a nozzle carried by the ring and discharging into the mixture passing through the ring; a connection between the chamber and the nozzle and a Venturi tube having a flanged base and seating on the ring in the fitting.
6. In a re-atomizer, the combination of a fitting having a seat therein and an annular groove forming one wall of a chamber; a re-atomizer ring seated in the seat in the fitting and forming with the groove a chamber receiving an ingoing liquid; a nozzle carried by the ring and discharging into the mixture passing through the ring; a connection between the chamber and the nozzle and a Venturi tube having a flanged base and seating on the ring in the fitting, the throat of the venturi being at the level of the discharge of the nozzle and the nozzle being in the form of a Venturi tube.

In testimony whereof I have hereunto set my hand.

FREDERICK O. BALL.
